US0D1012641S

(12) **United States Design Patent** (10) **Patent No.:** **US D1,012,641 S**
(45) **Date of Patent:** **** Jan. 30, 2024**

(54) **TOOL NOSEPIECE**

(71) Applicant: **HellermannTyton Corporation**,
Milwaukee, WI (US)

(72) Inventor: **Edward P. Dyer**, Germantown, WI
(US)

(73) Assignee: **Aptiv Technologies Limited**, St.
Michael (BB)

(**) Term: **15 Years**

(21) Appl. No.: **29/812,879**

(22) Filed: **Oct. 25, 2021**

(51) LOC (14) Cl. **08-05**

(52) U.S. Cl.

USPC **D8/51**; D8/44

(58) **Field of Classification Search**

USPC D8/14, 44, 51, 67, 68

CPC B21F 9/02; B25B 25/005; B65B 13/027;

B65B 13/22; B65B 13/345

See application file for complete search history.

(57) **CLAIM**

The ornamental design for a tool nosepiece, as shown and described.

DESCRIPTION

FIG. 1 is a right side perspective view of a tool nosepiece showing the design;

FIG. 2 is a left side elevation view thereof;

FIG. 3 is a front elevation view thereof;

FIG. 4 is a right side elevation view thereof;

FIG. 5 is a top plan view thereof;

FIG. 6 is a rear elevation thereof; and,

FIG. 7 is a bottom plan view thereof.

1 Claim, 4 Drawing Sheets
